UNITED STATES PATENT OFFICE

2,529,733

FIREARM

Rufus A. King, Wichita Falls, Tex.

Application December 26, 1947, Serial No. 793,851

1 Claim. (Cl. 42—40)

1

This invention relates to new and useful improvements in firearms and more particularly to tilting breech superimposed barrel shotguns.

As is well known, firearms of the tilting breech type having superimposed barrels, such as over-and-under shotguns, are preferred by many sportsmen due to the alignment of the bores of the barrels with the sight which renders the same more easily sighted and accurately fired. However, the vertically-aligned barrels offer greater cross-wind resistance and are, therefore, less desirable to use in windy or gusty weather. Since marksmanship is affected, to a considerable extent, by the familiarity of the individual with the firearm being used, it is objectionable to change to a single barrel or horizontally-aligned double barrel type. No two gun frames are identical and usually have different weights, grips and trigger pulls, although being of the same make and style. Any one of these differences, or a combination of slight variations in the same, is generally sufficient to affect one's marksmanship.

Therefore, one object of the invention is to provide an improved firearm of the tilting breech, superimposed barrel type having a double barrel frame and a single barrel assembly whereby the firearm may be used with interchangeable barrels and have substantially the same weight and feel while permitting the elimination of the additional wind resistance when so desired.

A particular object of the invention is to provide an improved firearm, of the character described, wherein the single barrel assembly is of such construction as to be capable of being readily mounted upon a conventional double barrel frame without altering the construction of the frame in any manner whereby said assembly is interchangeable with a conventional double barrel assembly.

An important object of the invention is to provide an improved single barrel assembly, of the character described, which may be constructed from a conventional superimposed double barrel assembly or which may be constructed so as to simulate the latter.

Another object of the invention is to provide an improved single barrel assembly, of the character described, having means simulating the lower barrel of a superimposed assembly and for mounting the same within a superimposed barrel frame whereby the action of the firearm is substantially unchanged.

A construction designed to carry out the inven-

2

tion will be hereinafter described together with other features of the invention.

The invention will be more readily understood from a reading of the following specification and by reference to the accompanying drawing, wherein an example of the invention is shown, and wherein:

Fig. 1 is a side elevation of a conventional tilting breech, superimposed barrel firearm,

10 Fig. 2 is a side elevation of a barrel assembly, constructed in accordance with the invention,

Fig. 3 is an enlarged side elevational view of the rear end or breech portion of the assembly,

15 Fig. 4 is a side elevation of the forward end of the firearm frame,

Fig. 5 is a rear elevation of the breech portion of the assembly, and

20 Fig. 6 is a view, partly in elevation and partly in section, showing the lower barrel simulating means.

In the drawing, the numeral 19 designates a tilting breech superimposed firearm or shotgun which is commonly referred to as an over-and-under. The gun includes a frame 11 having a stock 12 which is preferably provided with a pistol grip 13. A trigger 14 is carried by the frame 11 for actuating the usual hammer and firing mechanism (not shown). The fore-end of the frame indicated by the numeral 15, serves as a receiver for the rear end or breech portion of a barrel assembly 16 which includes a pair of axially aligned, superimposed barrels 17 and 18, a sight bead 19 and an anti-haze bridge 20. A pair of screws or pins 21 are carried by the frame fore-end 15 for pivotally supporting the barrel assembly 16 and a fore-grip or fore-stock 22 is removably attached to the lower barrel 18 for maintaining the connection between said assembly and frame fore-end. The assembly is locked in its closed position by a suitable latch 23 carried by the frame. The foregoing elements are more or less conventional and, in themselves, form no part of the present invention.

25 A barrel assembly 24, constructed in accordance with the invention is shown in Fig. 2, and includes an upper barrel 25, a sight bead 26 and an anti-haze bridge 27. A breech member or element 28, substantially identical to that of the conventional assembly 16, is connected to the rear end of the barrel 25. A conventional shell or cartridge ejector 29 extends longitudinally of the element 28 and is slidably mounted in a suitable keyway. The rear end of the ejector 29 is provided with the usual arcuate finger 30 which overlies the end of the barrel

in concentric relation to its bore 31. As shown by the dotted line in Fig. 5, the usual ejector for the lower barrel is omitted or removed. For actuating the ejector 29, a suitable arm 32 is pivotally supported by the frame fore-end 15, and coacts with mechanism (not shown) carried by the fore-grip 22. A pair of semi-circular recesses 33 are formed in the forward end of the breech element, on either side thereof, for receiving the pins 21 so as to pivotally support the barrel assembly.

A cylindrical member or tube 34 underlies the barrel 25 and has its rear end portion secured and engaging within the breech element 28. Although the member 34 may be solid, the same has been illustrated as being hollow and having a diameter substantially equal to the diameter of the barrel 25 for engaging within the fore-grip 22. If desired, the member 34 may be formed by cutting off the forward portion of the lower barrel of a conventional barrel assembly and closing the ends thereof by plugs 35 and 36, or by other suitable means. The rear plug 36 has an axial recess or depression 37 for accommodating the lower firing pin (not shown) which is carried by the frame 11. A latch or keeper 38 is secured to the lower portion of the member for cooperating with the lock (not shown) of the fore-stock 22. Manifestly, the member may be of any suitable construction so long as it provides a support for the barrel assembly 24. It is desirable to terminate the member adjacent or immediately forwardly of the fore-stock so as to provide a neat, finished appearance. In addition to simulating the lower barrel of a conventional assembly in appearance and functioning as a support, the member replaces to some extent the weight of said barrel and, if desired, may be additionally weighted.

From the foregoing, it is readily apparent that a novel barrel assembly has been provided. Due to its construction, the assembly is adapted to be used with a conventional superimposed, double barrel frame without making any change in the structure of said frame. Thus, the assembly is readily interchangeable with a conventional superimposed, double barrel assembly and may be used whenever it is desirable to reduce the cross-wind resistance of the assembly. Since the member 34 simulates the lower barrel of a conventional assembly, the feel of the firearm

remains substantially unchanged and the assemblies are so alike that the user of said firearm is not conscious of any change or difference of construction. The herein described single barrel assembly provides all of the advantages of a single barrel firearm, which is preferred due to its lightness and balance, as well as the identical trigger pull, stock and length of the superimposed double barrel firearm with which the user is accustomed.

The foregoing description of the invention is explanatory thereof and various changes in the size, shape and materials, as well as in the details of the illustrated construction may be made, within the scope of the appended claim, without departing from the spirit of the invention.

What I claim and desire to secure by Letters Patent is:

20 A single barrel assembly for a firearm of
the tilting breech type having a frame for re-
ceiving and supporting a superimposed double
barrel assembly and a cooperating fore-stock
including, a full length upper barrel, a lower
25 barrel member underlying and secured to the
inner portion of the upper barrel, the barrel
member being of such length as to be disposed
substantially wholly in the frame and fore-stock
with its outer end terminating at the medial
30 portion of said upper barrel when the barrel
assembly is mounted in said frame and said fore-
stock attached thereto, whereby the weight and
feel of the breech end of the double barrel as-
sembly is obtained and the cross-wind resist-
35 ance appreciably reduced.
